US0D1003013S

(12) United States Design Patent (10) Patent No.: US D1,003,013 S
(45) Date of Patent: * Oct. 31, 2023

(54) FOOTWEAR

(71) Applicant: Guoyu He, Jinjiang (CN)

(72) Inventor: Guoyu He, Jinjiang (CN)

() Term: 15 Years

(21) Appl. No.: 29/881,716

(22) Filed: Jan. 5, 2023

(51) LOC (14) Cl. 02-04

(52) U.S. Cl.

USPC D2/923; D2/916; D2/951; D2/953

(57) CLAIM

The ornamental design for a footwear, as shown and described.

DESCRIPTION

FIG. 1 is a perspective view of a footwear showing my new design;

FIG. 2 is another perspective view thereof;

FIG. 3 is a side view thereof;

FIG. 4 is an open opposite side view thereof;

FIG. 5 is a front view thereof;

FIG. 6 is a back view thereof;

FIG. 7 is a top view thereof;

FIG. 8 is a bottom view thereof;

FIG. 9 is a perspective view of the Footwear of FIG. 1 shown with the heel strap in an alternate position; and,
FIG. 10 is an enlarged view of the area labeled "10" in FIG. 2.

The broken lines showing of the footwear are for the purpose of illustrating portions that form no part of the claimed design.

1 Claim, 10 Drawing Sheets
